UNITED STATES PATENT OFFICE

147,268

DESIGN FOR A CLIP

Frank J. Gargano, Providence, R. I.

Application July 8, 1946, Serial No. 131,374

Term of patent 3½ years

(Cl. D45—19)

To all whom it may concern:

Be it known that I, Frank J. Gargano, a citizen of the United States, residing at Providence, in the county of Providence and State of Rhode Island, have invented a new, original, and ornamental Design for a Clip, of which the following is a specification, reference being had to the accompanying drawing, forming part thereof.

Fig. 1 is a plan view of a clip, showing my new design; and

Fig. 2 is an edge view of the same.

I claim:

The ornamental design for a clip, as shown.

FRANK J. GARGANO.
